(57) **CLAIM**

The ornamental design for a box for bits and/or tools, as shown and described.

DESCRIPTION

FIG. 1 is a top, front perspective view of a first embodiment of a box for bits and/or tools according to the design;

FIG. 2 is top, rear perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and

FIG. 8 is a right side view thereof.

FIG. 9 is a top, front perspective view of a second embodiment of the box for bits and/or tools according to the design;

FIG. 10 is top, rear perspective view thereof;

FIG. 11 is a top view thereof;

FIG. 12 is a bottom view thereof;

FIG. 13 is a front view thereof;

FIG. 14 is a rear view thereof;

FIG. 15 is a left side view thereof; and,

FIG. 16 is a right side view thereof.

The broken lines illustrate portions of the box for bits and/or tools and form no part of the claimed design.

1 Claim, 6 Drawing Sheets
